ABSTRACT: Apparatus for use in a bowling game having an automatic pinsetter. If the bowler bowls a strike after a coin is inserted in the apparatus visual indicating means are actuated. Time delay means ensure that the coin must be inserted before the ball is thrown.

APPARATUS FOR THE IMPROVEMENT OF BOWLING SKILLS

BACKGROUND OF THE INVENTION

The present invention is directed in general to apparatus for use with a bowling game having an automatic pinsetter for the improvement of bowling skill.

Increasing labor costs and a desire for greater efficiency and convenience have caused the automation of games of amusement such as bowling. However, with the attendant reduction of personnel in a bowling house and the necessary use of more technically oriented personnel the promotion of the game itself has suffered. Thus, there is a need for a promotional method or device especially adapted for use with an automated bowling game which is itself entirely automatic. Such a promotional device should stimulate the bowler to better his skill, be easy to operate, and should be dependable, automatic, and error free in operation.

OBJECTS AND SUMMARY OF INVENTION

It is therefore an object of the invention to provide apparatus especially adapted for use with a bowling game which stimulates the bowler to better his skill.

It is another object of the invention to provide apparatus as above which is automatic, dependable and error free in operation.

In accordance with the above objects there is provided an apparatus for use with a bowling game of the type in which a ball is rolled toward a group of pins and in which the number of pins knocked down are sensed by an automated device which provides a predetermined signal when all pins in the group are knocked down. This signal has a predetermined time duration. The apparatus comprises means for collecting coins and visual indicating means. Means including time delay means are responsive to the coin collecting means for coupling the automated device to the indicating means to provide a path for the signal. The time delay means delay this coupling for a time greater than the predetermined time duration. The indicating means is responsive to the signal to provide an indication that all pins have been knocked down.

BRIEF DESCRIPTION OF THE DRAWINGS

FIG. 1 is a perspective view of apparatus embodying the present invention;

FIG. 2 is a circuit schematic embodying the present invention; and

FIG. 3 is a timing diagram useful in understanding the present invention.

DETAILED DESCRIPTION OF PREFERRED EMBODIMENT

FIG. 1 illustrates a box 11 which would normally be placed between two lanes, for example lane number 1 and lane number 2, of a bowling house. The apparatus is divided into two halves, 11a and 11b, each half being associated with a particular bowling lane.

Each half includes externally a coin slot 12, a coin return button 13, and a coin return receptacle 14. A light under translucent plate 16 entitled "INSERT COIN NOW" tells the bowling player when to insert a coin in slot 12. A counter 17 counts the number of coins inserted. If the bowler makes a strike a strike light 18 is lit. Dashed line 22 indicates that there is a separate light for each half of the apparatus.

The apparatus of the present invention is most advantageously used in conjunction with the game of bowling or 10 pins. In addition, the bowling game should be automated in that an automatic pinsetter is used which automatically sets up the pins to be bowled down, indicates when all of the pins have been knocked down or strike is made by a light, indicates in the absence of a strike which pins have been knocked down, and in all other respects, duplicates the functions heretofore

manually performed to have the automated pinsetter function in accordance with the rules of bowling as adopted by the American Bowling Association. These include a game which is divided into 10 frames, each frame having a first and second ball cycle. In other words, for each frame the bowler normally would be provided with two opportunities to throw his ball twice at the pins if he fails to produce a strike or knock down all of the pins on his first ball. Thus, the automated pinsetting equipment is set up so that on the first ball it is in ball cycle number 1 and if a strike is made it is retained in that cycle. If only part of the pins are knocked down the so-called "deck" (a holder for the pins) as it is lowered senses the remaining pins standing and the pinsetter goes into its ball cycle number 2. This allows the bowler to throw his second ball and attempt to make what is termed a "spare." After the second ball is thrown the pinsetter then returns to ball cycle number 1 to begin another frame. The fact that the frame has ended is also signaled by another switch in the automatic pinsetter apparatus. Finally, if a strike is made another switch will provide an indication by light means of a strike.

The above essential switches are shown in FIG. 2 in the block labeled "pinsetter." The ball cycle switch is shown in its number 1 position meaning that it is the beginning of a frame and the pinsetter is ready to receive the first ball. This switch is of a bistable type. The other two switches labeled "strike switch" and "end of frame" switch are momentary close switches only which ground the appropriate line. They, as explained above, are actuated by the pinsetter. It should be emphasized at this point that although specific switches are shown and the switches when either closed or open ground a line, this is a representative showing only. In actual practice the specific circuitry of the automatic pinsetter would be coupled to in the most economical and simple manner. For example where isolation transformers are used a return line to the other side of the transformer coil would be used instead of ground. In addition, although a separate ball cycle switch and a frame switch are shown in some automated pinsetting devices, these might be combined.

The automatic strike indication feature of the pinsetter as discussed above provides the illumination of a so-called "strike light" when a strike is made. This light, in order to give the bowler adequate notice remains on a predetermined time duration. Concomitantly the strike switch will also remain closed this predetermined time duration to provide, in essence, a signal which indicates that a strike has been made.

Very briefly, the operation of the device, referring now to FIG. 1 again, allows the bowler to insert a coin in a coin slot 12 before rolling the first ball of the frame and if a strike is made strike light 18 will be illuminated. The illumination of light 18 is therefore an indication that the bowler has predicted he would bowl a strike and that he has done so. This is believed to place the bowler under stress resembling actual competition, thereby increasing his bowling skills and adding to his enjoyment of the game.

The specific circuitry for accomplishing the above, which is contained in box 11, is illustrated in FIG. 2. All of the circuit components as illustrated are coupled to a low voltage source which is preferably 24 volts. This reduces any shock hazard. The voltage may be obtained from any convenient location but in the preferred embodiment it is obtained from the pinsetter itself. This is most convenient since several control wires, such as to the strike switch and the frame switch, must also be coupled into the pinsetter automated mechanism.

More specifically, the circuit of FIG. 2 includes two bistable relays generally indicated at 23 and 24. Relay 23 includes set and reset coils, so labeled, which are coupled to a moving contact arm 26. The arm is shown in its initial or reset condition. Similarly, relay 24 includes set and reset coils with moving contact arms 27 and 28, both of which are in their reset positions.

A coin drop switch 29 couples the set coil of relay 23 to ground through the ball cycle switch of the pinsetter. Thus, as soon as a coin is dropped in slot 12 it, in essence, closes the

switch and completes the circuit through the set coil between the voltage source and ground thereby actuating moving arm 26 into its other or set position. In this position arm 26 is coupled through a time delay relay 31 which includes a time delay coil 32 and a switch 33. The time delay of time delay coil 32 is adjusted by rheostat 34 which is coupled to the 24-volt source. Switching arm 26 connects the other side of the time delay coil 32 to ground through the number 1 ball position of the ball cycle switch. After a predetermined time delay of, for example 10 seconds, switch 33 of the time delay relay 31 is closed coupling the reset coil of relay 23 to ground through position number 1 of the ball cycle switch. At the same time the set coil of relay 24 is also coupled to ground thereby actuating relay 24 to move arms 27 and 28 to their other or set position. Thus, the set coil and the reset coil of relay 23 are interlocked so that the phasing between the two relays is always maintained.

Arm 27 is coupled to the strike switch of the pinsetter which is normally in an open condition and only momentarily closes to ground upon a strike indication. In its set position switch arm 27 couples to a parallel circuit containing three legs all terminating at the 24 volt source. One leg contains strike light 18 which is in series with a flasher device which opens and closes the circuit at a predetermined rate to flash the light 18. The counter 17 is also actuated when light 18 is flashing.

Switch arm 28 of relay 24 in its reset position couples through switch arm 26 and thus to the ball cycle switch. An "INSERT COIN NOW" light 16' is in parallel with coin accept mechanism 37. Both light 16' and coin accept mechanism 37 are coupled to the 24 volt voltage source.

Lastly, the reset coil of relay 24 is coupled to the "END OF FRAME" switch which when momentarily closed at the end of the frame actuates the reset coil to return relay 24 to its reset position as shown.

OPERATION

The present invention can be best explained by dividing its operation into several phases. In its phase "A" the pinsetter has been activated and the ball cycle switch is in cycle number 1 meaning that the bowler is at the beginning of a frame where the first ball is to be thrown. At this time relays 23 and 24 are in their reset positions and time delay switch 33 is open. Also, at this time the coin accept device 37 along with the "INSERT COIN NOW" light 16' are both activated through switch arm 28, switch arm 26 of relay 23, and the ground of the ball cycle switch to indicate to the bowler that he may insert a coin in slot 12.

If a coin is inserted in slot 12, coin drop switch 29 is closed to shift the circuit into its phase "B." If the coin is sensed by the coin accept mechanism to be a good coin it is accepted and the switch 29 is closed. Such coin accept devices are well known in the art and may be purchased as a standard unit with the proper output switch. Closure of switch 29 energizes the set coil of relay 24 to move switching arm 26 into its set position to energize time delay coil 32. At the same time the movement of switch arm 26 has opened the circuit to the "INSERT COIN NOW" light 16' and the coin accept coil 37; thus, the light is extinguished. Any additional coins inserted will automatically be returned through the coin receptacle 14 (FIG. 1). The time delay heater 32 may be adjusted by means of rheostat 34 between 5 and 15 seconds. The significance of this adjustment will be explained below. After the predetermined time duration switch 33 is closed the circuit enters its phase "C."

In phase "C" closure of switch 33 couples the reset coil of relay 23 to ground through the ball cycle switch to cause the relay to be reset to the position as shown. This takes the time delay coil 32 out of the circuit and opens switch 33. However, during the momentary closure of switch 33 the set coil of relay 24 was also coupled to ground through the ball cycle switch to set relay 24. This action caused switch arm 28 to move to an open or set condition to maintain insert coin light 16' off

despite the resetting of arm 26 of relay 23. Also, the coin accept device 37 is maintained off to again return any coins to the bowler inserted at this time.

The closure of switch 33 and setting of relay 24 has also moved switch arm 27 into contact with the circuit containing the strike light 18. Thus, the strike switch of the automated pinsetter is now coupled to the strike light 18 so that any activation of the strike switch by the pinsetter mechanism will activate the strike light 18; in other words, a signal path is completed between the strike switch and light 18. In addition, counter 17 is ready to count such token if a strike is made. Note that the counter 17 can also be placed across the set coil of relay 23 to count the number of coins played.

If the bowler knocks down all of the pins and gets a "strike" phase "D" of the operation is entered. In this phase the strike switch has closed for its predetermined time duration which is usually approximately 10 seconds. This causes strike light 18 to flash indicating to the bowler that he has made a strike.

In the last phase "E" of operation the strike switch opens after 10 seconds and the end of frame closed to actuate the reset coil of relay 24. This resets the circuit to its initial condition. In this condition switch arm 28 of relay 24 causes "A." light 16' to be lit and the coin accept device 37 to be ready to accept the coin. Thus, it is now in phase "A"

If no strike is made then the ball cycle switches from position number 1 to number 2. This opens the ground through switch arm 28 to the insert coin light 16' to thus disable it. In addition, the coin collecting means 37 are disabled also to prevent the accidental collection of a coin if one should be inserted.

The resetting of relay 24 in addition to deactivating insert coin light 16' through switch 28 opens the path between the strike switch and the strike light 18. This resetting is, of course, accomplished by the end of frame switch which, in essence, indicates the end of a particular sequence of operations of the bowling device when two cycles are completed.

FIG. 3 is a timing diagram of a preferred mode of practicing the invention showing the usefulness of the time delay period which is indicated. As illustrated, this time delay period has been given a nominal value of 12 seconds; the time duration during which the strike light is on is 10 seconds. This time duration occurs as indicated at the beginning of the closure of the strike switch and continues until the end of frame.

The operation is graphically shown along the abscissa line 40 starting where the previous frame has ended and the apparatus has been cycled back to its phase "A" where all relays are reset. As shown, the "INSERT COIN NOW" light is illuminated. When the coin is inserted this has been designated time zero. For the average bowler 4 seconds will elapse until the ball is thrown, two seconds until a strike occurs, and two additional seconds for the deck on the pinsetter to descend to sense that all pins have been knocked over. At this point the strike switch is closed. The time delay period indicated at 41 illustrates the time at which the time delay relay has been initially activated and when switch 33 will close. This switch, of course, must be closed to activate relay 24 and complete the path between the strike switch and the token ejector 36. Thus, at the end of the time delay period if the strike light of the automatic pinsetter is on at that time the completion of the path will cause the activation of light 18.

Thus, it is apparent that the end of the time delay period must occur, if the apparatus is to function effectively, within the "strike light on" period. The purpose of this time delay period is largely to prevent a bowler from inserting a coin in the apparatus after the strike occurs and he thereby being given an erroneous light 18 indication. Thus, the operation of the time delay period is indicated by the dashed lines 42 where if the bowler watches a strike occur and then after a second has elapsed inserts a coin in the apparatus the switch 33 of the time delay relay will not close until after the end of frame indication has occurred. If switch 33 does close to complete the path to the strike switch by the setting of relay 24, no effective action will take place since the strike switch has already

opened. Thus, it is apparent that the time delay period must be longer than the time duration the strike light is on (preferably 12 or 13 seconds) to prevent defeating the operation of the apparatus.

On the other hand, the time delay period must not be so long as to cause the time period 41 to exceed the "strike light on" period. This might occur with a relatively fast bowler who, after inserting a coin immediately makes his approach and throws the ball at a relatively high velocity to cause the strike to occur in perhaps 4 seconds. Assuming a 2-second period between the occurrence of the strike and the time at which the strike switch is activated this would mean that the maximum time delay period is the "strike light on" period of 10 seconds plus 6 seconds. Therefore, the maximum time delay is 16 seconds.

Thus, in summary the present invention has provided an improved apparatus for use with a bowling game which improves the skill of the bowler by placing him under competitive stress. Moreover, the apparatus is economically integrated into the automatic pinsetting mechanism and is dependable and error free in operation.

We claim:

1. An amusement apparatus for use with a bowling game of the type in which a ball is rolled toward a group of pins and in which the number of pins knocked down are sensed by an automated device which provides a predetermined signal when all pins in said group are knocked down, said signal having a predetermined time duration, said apparatus comprising, means for collecting coins, indicating means, and means including time delay means responsive to said collecting means collecting a coin for coupling said automated device to said indicating means to provide a path for said signal, said time delay means delaying said coupling for a time interval greater than said predetermined time duration said indicating means being responsive to said signal for providing an indication of all pins being knocked down.

2. An amusement apparatus as in claim 1 in which said time delay means delay said coupling no longer than said predetermined time duration plus the time needed for a relatively fast bowler to insert a coin in said collecting means and roll a ball toward said pins.

3. An amusement apparatus as in claim 1 in which said time

delay is no longer than said predetermined time duration plus 6 seconds.

4. Apparatus as in claim 1 including means for disabling said collecting means.

5. Apparatus as in claim 4 in which said automated device includes means for indicating two different cycles of said game and in which said disabling means is responsive to one of said cycles for disabling said collecting means.

6. Apparatus as in claim 1 together with means for opening 10 said path to said indicating means.

7. Apparatus as in claim 6 in which said automated device includes means for indicating the end of a particular sequence of operations of said game and in which said uncoupling means is responsive to said indication to open said path.

15 8. Apparatus as in claim 1 together with means for indicating when said apparatus is in a condition to receive a coin and for interlocking said collecting means with said indicating means so that collecting of a coin disables said indication.

9. An amusement apparatus for use with a bowling game of 20 the type in which a ball is rolled down a lane toward a group of pins and in which the number of pins knocked down are sensed by an automatic pinsetter which provides a strike signal of a predetermined time duration by means of a strike switch and also includes ball cycle and end of frame switches, and apparatus comprising, first and second relays each having set and reset actuating coils said second relay including first and second switches, a coin drop switch coupled to said set coil of said first relay for activating said coil, means for accepting coins, indicating means, a time delay switch coupled to said 25 reset coil of said first relay for resetting said relay, said coin drop switch and said time delay switch being coupled together and terminated on said ball cycle switch, said set coil of said second relay also being coupled in parallel with the reset coil of said first relay and said reset coil of said second relay being terminated to ground through said end of frame switch, said first relay having a moving switch arm which in its set position couples an actuating coil of said time delay switch to said ball 30 cycle switch and in a second reset position couples said ball cycle switch to said first switch of said second relay which completes the circuit to said coin acceptor means said second 35 switch of said second relay in its set position coupling said strike switch to said indicating means.
